C. G. A. BRICKMANN.
CIGAR MACHINE.

No. 44,070.

Patented Sept. 6, 1864.

UNITED STATES PATENT OFFICE.

C. G. A. BRINCKMANN, OF NEW YORK, N. Y.

CIGAR-MACHINE.

Specification forming part of Letters Patent No. 44,070, dated September 6, 1864.

To all whom it may concern:

Be it known that I, C. G. A. BRINCKMANN, of New York, of the county of New York, in the State of New York, have invented certain new and useful Improvements in Machinery for Making Cigars; and I do hereby declare that the following is a full and exact description thereof, reference being had to the accompanying drawings, making part of this application.

Previous to my invention machines have been made in several ways adapted to perform the operations necessary to manufacture cigars; but in all the machines of which I have any knowledge many radical defects or objections exist which I propose by my invention to effectually overcome.

The most successfully operating machines which have been heretofore made have been those in which the operation of covering the bunch (to form a cigar) has been performed between endless moving bands, and having conically-shaped headers or cone-like cavities, within which the head of the cigar was formed by compressing the blunt end of the bunch or core, and working it into a conical form while wrapping it with the outside or covering leaf of tobacco. This kind of machine has been made with the endless bands arranged and traveling in a direction about at right angles to the axis of the cigar, and also with the said bands arranged so that one would move across the other in a slightly-oblique direction instead of at right angles to the cigar. The principal practical difficulties encountered in the use of these two modes of construction may be thus briefly stated: first, the impracticability of compressing into a conical form the blunt (cut off square) end of the core or bunch, especially during the operation of wrapping or covering the bunch; secondly, in that kind of endless-band machine in which the bands run both at right angles to the cigar-stock, it is a very difficult matter to guide the wrapper so that its hook will come up to the right point to perfectly form the conical head of the cigar, and hard to regulate the tension on the wrapper to make it wind evenly and tight over the core or bunch without breaking the wrapper; thirdly, on account of the natural tendency of the yielding or elastic bands to assume straight lines and come together where the cigar is

confined between them there is a tendency to roll the cigar oval or irregular in cross-section and to compress the core too much; fourthly, there is great difficulty in forming the conical head well, the surfaces between which it turns being perfectly dead or stationary, while the cigar turns therein; fifthly, in the machines in which the endless bands were run obliquely across each other, one passing at an angle to the axis of the cigar, (the same defects relative to forming the conical head existed,) and the tendency and effect of the obliquity of the rolling band was to twist the core or bunch and make it too tight or solid and thus spoil the cigar; sixthly, in that kind of machines in which the rolling bands or surfaces ran both at right angles to the axis of the cigar, it was necessary, in order to work them at all, that the core and cigar formed should be just about a given length and size, or a failure in the cigar produced was the result, while in that kind in which one of the bands passed obliquely across the cigar the latter would often be forced too hard up toward and into the conical socket, thus twisting and ruffling up the wrapper, and the core of the cigar would be often twisted, spoiling it entirely. There are other difficulties (in tucking the wrapper, &c.) in working these machines which can only be partially overcome by a most expert operator, so that they have not proved successful and beneficial inventions so far. There have been other kinds of cigar-machines suggested and operated than those particularly alluded to; but as they have not worked even so well as those mentioned, I will not allude to them here.

My invention has for its objects an apparatus or machine for forming cigars, so constructed and organized that it shall be capable of forming cigars perfectly and of different lengths and diameters, and may be successfully worked by any person of very slight experience; and to these ends my invention consists in the use of conically-shaped formers, having their extreme points flattened in connection with a pair of knives or other device for cutting, the whole so arranged as to form the bunch or core of the cigar, with a nearly conical head, as hereinafter more fully explained; and my invention further consists in the employment of a series of cylindrical rolls

arranged so as to confine the core or bunch of the cigar between them and roll it with a yielding or elastic pressure, as hereinafter more fully set forth; and my invention further consists in making the header-blocks or the concave boxes between which the conical head is formed yielding, so as to adapt themselves to different sizes and conditions of the head of the cigar and more perfectly form it; and my invention further consists in so hanging or arranging the yielding rolls that they will yield more readily—that is under less pressure—at one end than toward the other, as hereinafter more fully explained, for the purpose of rolling the stock up toward the head of the cigar and perfectly forming and covering the latter; and my invention further consists in the employment of a rod or its equivalent running about parallel with the rolls, and so arranged as to press against the bunch or core while being covered, and cause the wrapper to wind tight on the core and "tuck" fast, as hereinafter more fully described; and my invention further consists in providing the header-blocks or sockets with inserted rolls, (or extending one of the main rolls into each of them,) for the purpose of giving motion to the surface of the conical sockets to decrease the friction and form the head perfectly, as hereinafter more fully explained; and my invention further consists in providing the conical sockets or header-blocks with a stop or cut-off rod at their extremities, as hereinafter explained, for the purpose of preventing the hook or any portion of the wrapper from passing out between the two sockets or blocks, and rendering the point or conical tip of the cigar imperfect; and my invention further consists in the use of a traveling guide, on which the operator places and holds the hook end of the wrapper, and which guides the hook in such manner as to always bring it up just right to the header to form the conical end of the cigar perfectly, as will be hereinafter more fully explained; and my invention further consists in the use of a traveling guide on which the operator places and holds the hook end of the wrapper, and which guides the hook in such manner as to always bring it up just right to the header to form the conical end of the cigar perfectly, as will be hereinafter more fully explained; and my invention further consists in the employment of an adjustable and slightly-yielding stop, against which the butt or blunt end of the cigar comes, and which stop serves to keep the cigar being formed up toward the header without forcing it too hard in that direction, as hereinafter more fully set forth; and my invention further consists in a novel and peculiar method of gearing the rolls together, as hereinafter explained; and my invention further consists in the combination, with the series of rolls, of regulator-plates or their equivalents for causing the several rolls to yield equally or to the same extent, as hereinafter set forth; and my

invention further consists in forming the rolls with fine serrations or ridges running longitudinally, whereby they are caused to operate in a more desirable manner on the leaf of tobacco in covering the cigar.

To enable those skilled in the art to make and use my new machine, I will proceed to describe its construction and operation, referring by letters to the accompanying drawings, forming part of this application, in which—

Figure 1 is a top view of my machine. Fig. 2 is a vertical section at xx , Fig. 1, looking in the direction indicated by the black arrow. Fig. 3 is a vertical section at yy , Fig. 1, looking in the direction indicated by the red arrow. Fig. 4 is a detail cross-section of gearing at zz , Fig. 1. Fig. 5 is a detail vertical section at line 66 , Fig. 1. Fig. 6 is a partial top view showing the wrapper-guide in another position. Fig. 7 is a detail top view of lower half of header-socket; Fig. 8, vertical section (of both sockets) at Aa , Fig. 7. Figs. 9 and 10 are detail views which will be presently explained. Fig. 11 is a similar view to Fig. 7, but showing another modification of the same part. Figs. 12 and 13 are detail views of adjustable stops.

In the several figures the same part of the machine is indicated by the same letter of reference.

A represents the base of the machine, which may be of any size and shape deemed expedient. (I propose to make it somewhat after the fashion of a sewing-machine table supported by suitable legs.) On this table are secured or formed two upright stands, B B', which are provided with two caps, C and C', hinged to said stands on one side and united over their top by a plate, D, and in said stands and caps are arranged the boxes V V, &c., in which the journals of the series of rolls E are hung. These boxes V are arranged to slide in slots cut in the stands B and B' (see Figs. 2 and 3) radially—that is to say, in direction converging a point co-incident to the center of the circle in which the rolls E are arranged—and have arranged in connection with them springs O, which exert a constant tendency (when the rolls are pressed away from a line denoting the axis of a cylinder in the periphery of which the rolls E are located) to cause the rolls E to approach each other. The rolls E are provided at one end with pinions f f, &c., which mesh into a driving-pinion, I, the shaft a^5 of which is hung in a stand, E², and is provided with a suitable means of applying the motive power to operate the machine. On the stud a^5 is also hung a gear, C¹, which meshes into a similar gear, D¹, on the shaft K. This shaft is mounted to turn freely in stands F¹ and L, (see Fig. 1,) bolted to base A, and is provided at its other end, (opposite to that on which gear D¹ is,) with a pinion, M, which meshes into the rack O of the wrapper-guide, and also into a pinion, N, on shaft D², (which is supported in the stand E².) The rack O is arranged on the top surface

of a plate, Q, in such a manner, having pins $f^2 f^3$ that pass through slots C³ in said plate, as that said rack O can move laterally (from side to side) on said plate Q, but cannot move longitudinally thereon. This rack O is periodically moved from one side to the other of the top surface of plate Q, and is driven alternately by pinions M and N, as will be presently explained. As the rack O travels longitudinally, it carries with it the plate Q, which is so arranged as to slide in suitable bearings (or on ways) in tops of two stands, P P, on the lower surface of Q. Near its center is a stop, S, which comes against springs R R, (see Figs. 1 and 2,) for purposes to be presently explained. U U are two stands, in which are arranged two sliding bars, W and w', the former of which is made with a cam-like end and the latter with a square end. Each is provided with a spiral spring, b² b³, and stop-pin X, and the two are connected by a cross-bar, c¹, so that they must move together or simultaneously. V V are two other stands, in which are two other bars, A² and d², provided with cross-bars e², springs b² and d², and constructed to operate as the set of bars just before referred to. The offices and operations of these two sets of sliding bars will be presently explained. J and J' are the two conical sockets which constitute the header, between which the conical head of the cigar is formed, and which are connected to the stand B' and its cap C'. The lower one, J', has extending up from it, near its apex, a stop-bar, g, (in the form of the arc of a circle,) which passes through the upper one, J. (See Figs. 7 and 8. These socket-blocks J J' are so arranged as to yield when pressed against by the confined head of the cigar being formed, and are provided with minute anti-friction rolls s, (see Fig. 7,) or in lieu thereof the rolls E may be extending into said block J J', as shown at Fig. 11. As before remarked, the caps C and C' (in which are hung three of the rolls E) are hinged to the stands B B', and connected by a top plate, D. One of said caps, C, is formed or provided with a projecting handle, a, by means of which said caps and their attachments are swung up and down and which catches under a spring-lip, b, (see Figs. 1 and 3,) to lock the said caps down.

F is a shaft hung in the line of the hinges of caps C C', and provided with boxes p p', (see Fig. 1,) into which work the shanks n n of the rod n¹, which shanks work against springs r r' in said boxes p p'. Said shaft is slotted through horizontally from 4 to 5, to accommodate the bar h. This bar is secured at either end to sliding boxes i i, arranged in grooves in the stands H H, and is provided near its center with a block, G. This block G is formed so as to about fill the central space (in cross-section) between the rolls E E (see Fig. 2) and has a revolving center, g, (see Figs. 12, 13,) against which the blunt or butt end of the cigar presses while being formed. The blocks

i i have each attached to them rods j, that connect onto springs k attached to chains l, which pass through eyes in a cross-bar, m, where they are fastened by pins h².

Immediately over the plate Q is a narrow plate or strip, T, supported on short studs w, which serves for the operator to rest and hold the hook end of the wrapper on, as will be directly explained.

c c' are the regulator-plates, which are arranged against the outer face of stand B, and secured, respectively, to the sliding boxes of the uppermost and lowermost of the rolls E by means of screws 2 3. (See Fig. 5.) These plates c c' are so shaped that their curved edges confine the other four rolls E and prevent them from moving outward (away from the axis of the system of rolls) to any greater extent than the top and bottom rolls of the series move.

Before proceeding to explain the operation of the machine, the construction of the parts of which I have just explained, I would remark that the bunch or core is formed in another machine, which may be a duplicate of this, except in the header-sockets. In the machine in which I form the bunch or core (preparatory to putting on the wrapper, thus finishing the cigar) the header or concave sockets are made in all respects like those already described, except that they do not extend to an apex or sharp point, but are formed like a cone, (or of a conical form,) with the apex cut or slabbed off, as seen at A⁴, Figs. 9 and 10, and are provided with knives or shearing-blades b⁵ and c⁵, as illustrated at Figs. 9 and 10. I propose, also, to have the series of rolls open apart and close together (for the insertion and removal of the stock) on a different line from that shown at Fig. 3, as seen at Fig. 9, but need only state here that it must be borne in mind that the bunch or core produced by it has a conical end with the extreme end or tip cut off, as illustrated at Fig. 14.

The core or bunch, such as seen at Fig. 14, is placed between the rolls E, as indicated by the red circles at Fig. 3, when the cap C is closed down, the wrapper being started on the butt-end of the core (in the usual manner,) and the stop G being brought up to just about touch the butt of the core, while its conical end lies just in the socket J J'. The operator rests the hook of the wrapper (its point) on the top of wrapper-guide, plate T, so that the wrapper runs from the butt-end of the cigar to said plate T, forming with the line of the plate T and the axis of the cigar-core the hypotenuse of a right-angled triangle. I am now supposing the wrapper-guide T, with its traveling bed Q, to be in the position (relatively to the socket J J') seen at Fig. 6. The machine is now put in motion by the application of any motive power to the main driving-shaft a⁵, and as the cigar-core is revolved between the rolls E by their rotation the wrapper is smoothly and tightly wound around it, the

hook being held firmly down on the plate T by the operator's hand, (or finger,) and traveling always toward the header-socket J J', into which it finally passes, and is there wound round the partially-conical head of the core in such manner as to complete the conical head of the cigar.

The condition of parts shown at Fig. 1 represents the progress of this operation; but by the time the wrapper has been completely drawn into the machine and envelops the core the rack O has traveled so far (in the direction indicated by red arrow, Fig. 1) as to have run out from under its driving-pinion N, and the stop S on under side of plate Q has come about up to the spring R'. (See Fig. 2.) At this stage of the proceedings the operator (by means of a treadle or in any other desirable manner) presses the bar e² in the direction indicated by arrow, Fig. 1, which causes the cam-like end of bar A² to come against the periphery of wheel B² and wedge the plate or traveling bed Q still farther in the direction indicated by red arrow, Fig. 1, and causes also the square end of bar d² (which is now also opposite the center of rack O) to push the rack O bodily and laterally to the other side of plate Q, as seen at Fig. 6, and the stop S to push back the spring R'. The operator then releases bar e², which, together with bars A² and d², is forced back to its normal position by springs b². Simultaneously with this movement of the bar A² and d² the spring R', acting against stop S, forces the plate Q in a direction opposite to that in which it was just before traveling, and the rack O is thrown in mesh with the pinion M, which now drives it in an opposite direction, carrying it back to the position shown at Fig. 6. Meantime the cigar, if deemed expedient, is being rotated or revolved between the rolls E and its wrapper nicely smoothed over the core and the conical head finished up. The operator lifts up the handle a, raising the upper three roll E, as seen at Fig. 3, and taking out the finished cigar inserts another core to be covered or wrapped, and pressing the bar C² in the direction indicated by black arrow (see Fig. 1) causes the bars W and w' to operate on the plate Q and rack O in a manner similar to that just explained of bars A² and d², to force the rack O over the other side of plate Q and put it in mesh with pinion N again, when another wrapper is started in and the operation of winding it on just described is repeated to complete another cigar. The stop d is adjusted by means of chains l and lock-pins h² to suit the length of the cigar being manufactured, and is set so it just touches the butt of the core. Now, then, as the core or bunch is compressed between the rolls E its butt-end will press against stop G, which, by reason of springs k k will yield, but at the same time will exert a gentle and continuous pressure against the end of the core, tending to force it up toward the header J J'. When the core is laid in

and the end of the wrapper started around it, the rod n⁵ (see Figs. 1 and 2) operates to hug the end up against the core tight and effect a perfect tuck, so that the wrapper may be more readily wound tight, and as the operation progresses this rod n⁵, which, it will be remembered, is yielding and yields less readily (under more force) at the butt-end of the cigar than nearer the head, exerts a constant tendency to press or scrape gently against the side of the cigar and thus cause the wrapper to wind on tight and smooth, and also work the cigar constantly up toward the conical header, but with a gentle and yielding pressure.

The object of making the springs O of all the yielding rolls E stronger at the ends nearest the butt of the cigar, is to cause the rolls E to press hardest against the cigar nearest its butt, whereby the cigar is properly shaped and the stock forced gently and continuously toward the header J J'. The pinions I and f, it will be seen, have their teeth so shaped as to mesh properly when the rolls E are pressed out by the stock contained between them, (that is, away from the common axis of the system of rolls,) as well as when in their normal positions, and the pinions f are so arranged around the main pinion I that they are all driven by it without interfering with each other, and being at the same time so small as to admit of bringing the rolls E sufficiently close together to form a small cigar. In the drawings I have drawn the machine three-quarters the size of a working machine adapted to make cigars varying in diameter (at the largest part) from the diameter of a three-cent silver piece up to the diameter of a nickel one-cent piece. It is very necessary that the rolls E should all be capable of yielding, and yet that the extent of movement of each should conform to that of the others. This end I accomplish by means of the regulator-plates e and c' before described.

The pinions M and N and rack O should be made of such a pitch relative to pinions f f and I, and circumference of rolls E, as that latter will take up the wrapper in proportion to the velocity at which the wrapper guide-plate F moves.

By the employment of some such means as shown and described, or the equivalent thereof, of rendering a portion of the surface of the conical cavity in which the head of the cigar is finished, capable of moving with the moving surface of the stock of the cigar, the conical head is more smoothly and perfectly formed.

The header-blocks J J', it will be seen, swing down together so as to form a solid-like block (with a conical cavity within) except at 10 10, (see Fig. 8,) where each of them is cut away very slightly, so as to allow of the passage of the wrapper-leaf to the head of the cigar. As the two halves of the header J J' form a joint or crack where they come together into or through which the tobacco-leaf might work at

the extreme point of the cigar-head, thereby spoiling the head, I provide as a preventive to this a stop-wire, *q*, extending up from the lower block, *J'*, in the arc of a circle, through the upper one, *J*, in such manner as to form an abutment, as it were, at the apex of the conical cavity, and yet admit of the swing-up of the upper position of the header-socket.

It will be obvious that my new machine is subject to many changes in the details of its construction without departing from the spirit of my invention or changing the modes of operations involved in the machine.

Having fully explained the construction and operation of my machine, so that one skilled in the art could make and use it, and not wishing it to be understood that my invention is limited to the precise detail of construction shown and described, what I claim as new, and desire to secure by Letters Patent, is—

1. Forming the core or bunch with a nearly conical head, that is—corresponding to the shape of the finished cigar, except in having its tip cut off, substantially as shown and described, for the purpose set forth.

2. The employment of a series of yielding rolls adapted to receive and turn the cigar-core between them in the manner substantially as hereinbefore set forth.

3. The employment of header-blocks *J J'*, mounted in such manner as to yield to the pressure exerted upon them, in the manner and for the purpose described.

4. So arranging each of the rolls *E* that it

will yield under less pressure near the end intended to be nearest the butt of the cigar, substantially as and for the purposes set forth.

5. The employment of the spring-rod *N*, or its equivalent, as and for the purposes set forth.

6. Combining with the header-block a socket, inserted rolls, (or a continuation of the main rolls,) for the purpose of decreasing the friction or dragging tendency on the surface of the cigar-head.

7. The employment, in combination with the header-blocks, of the stop-rod *q* or its equivalent, arranged to operate as and for the purpose set forth.

8. The employment of an automatic guide on which the hook of the wrapper may be held, and by which it will be guided, substantially as and for the purpose described.

9. The employment, in combination with the rolls and header-blocks for forming and wrapping the cigar, of an adjustable springing stop *G*, as and for the purpose set forth.

10. The combination, with the rolls *E*, of regulator-plates *c c'*, or their equivalents, the whole arranged to operate substantially as and for the purposes described.

In testimony whereof I have hereunto set my hand and affixed my seal this 18th day of May, 1864.
